RENÉ PICARD, OF PARIS, FRANCE.

MILEAGE AND TIME INDICATOR FOR VEHICLES.

1,312,747.

Specification of Letters Patent.

Patented Aug. 12, 1919.

Application filed June 25, 1913. Serial No. 775,811.

To all whom it may concern:

Be it known that I, RENÉ PICARD, citizen of the French Republic, residing at 133 Boulevard Ney, Paris, France, have invented 5 certain new and useful Improvements in Mileage and Time Indicators for Vehicles, of which the following is a specification.

This invention relates to taximeters in which the registering mechanism is driven 10 from a clock or from a road wheel of the vehicle by whichever is going at the faster rate, and has for its object to provide an improved efficient mechanism by means of which the driving arrangement of the apparatus 15 may be adjusted at will for one of several preferably three tariffs. To this end according to this invention, the mechanism is provided with worms driven from the vehicle and adapted individually to be 20 coupled with a main driving shaft with the aid of a stepped coupling barrel, for the purpose of obtaining either of the three different tariffs, as will be hereinafter fully described with reference to the accompanying 25 drawings, in which:—

Figure 1 is a sectional elevation of the improved driving arrangement.

Fig. 2 is a sectional elevation as seen from in front of Fig. 1.

30 Fig. 3 is a plan view of Fig. 1.

Fig. 4 is a section of the improved main driving shaft.

Fig. 5 is a development of the stepped barrel or clutch sleeve.

35 Fig. 6 is a front view of the hour pinion. According to this invention as shown the three different tariffs are governed by three worms 1, 2, and 3 (Fig. 2) adapted to mesh with three worm wheels A, B and C respectively, which are loose on the main driving 40 shaft q and drive ratchet wheels d , e and e' respectively, fixed on the main driving shaft by means of pawls such as b' mounted on the worm wheels respectively. These worm

45 wheels may have a variable number of teeth according to the three tariffs in use. Each of the three tariffs is obtained by connecting each screw with two half-clutches 4 and 5, 6 and 7, 8 and 9, which impart to the corresponding screw the driving movement for 50 the particular tariff to be used. This coupling action is effected by means of levers 10, 11 and 12 similar to the lever 11 shown and controlled by three cams a , a' and a'' indicated in Figs. 1 and 3, mounted on the cam or flag shaft F. The rotary movement

of the worms 1, 2, 3 is obtained by means of toothed wheels of equal diameter 13, 14 and 15 which are in constant engagement and of which one, 14, is arranged upon an intermediate spindle 16, provided with a toothed wheel 17 which is in engagement with a toothed wheel 18 of the same diameter as 17 and fixed upon a worm 19 which is driven by the flexible connection from the wheels of the vehicle. 60

A coupling sleeve f adjustably mounted on the shaft q is rotated thereby with the aid of a pin i which is fixed on the shaft.

This pin projects through a slot arranged 70 in f parallel to the axis thus enabling f to be displaced in a longitudinal sense which in the usual manner is effected by means of a cam actuated lever (not shown) from the flag or setting shaft F. This sleeve f is provided with a coupling finger f' and the driving takes place in the following manner: 75

Supposing for the following tariffs the charge would be at the rate of 25 cents per 1000 meters compiled of fractions of 166 80 meters for tariff I, 125 meters for tariff II, and 100 meters for tariff III, so that for tariff I the fraction amounts to one-sixth of the rate, for tariff II one-eighth, and for tariff III one-tenth. Assuming the three 85 wheels A, B and C to have respectively 66, 50 and 40 teeth, it will be seen that if one tooth corresponds to 25 meters, one revolution of the driving shaft when using tariff I will correspond to 25×66 , which equals a 90 distance of 1650 meters; for tariff II 50×25 , equaling 1250 meters, and for tariff III 40×25 equaling 1000 meters.

It is the usual practice for the driver of a taxicab, when he takes up a passenger to 95 operate the taximeter so that an initial charge is registered, and the taximeter then registers no further charge till the distance corresponding to the initial charge has been traversed.

Now in order to obtain this last motion and then to transmit movement from the wheels A, B and C to the registering mechanism according to the particular tariff for which the whole apparatus is set, this invention provides as a transmitting medium a stepped barrel g which by means of a sleeve-shaped hub g' is journaled on the driving shaft q and partly embraces the sleeve f . In the example shown, (Fig. 5), 110 this barrel has its face cut away at three different levels g^2 , g^3 and g^4 each provided

for a definite delay of the driving engagement for the particular tariff. In Fig. 5 the whole circumference of the face of the barrel is assumed to be divided into ten equal units. Each individual step or face g^2 , g^3 , g^4 is adapted to engage with the finger f' of the sleeve f when the latter is displaced within its slot to bring about the desired engagement.

- 10 Each revolution of the shaft q will comprise the whole of the 10 divisions of the barrel g and when the apparatus is set for tariff I, the mechanism will not commence registering until after the shaft has performed sixth-tenths of one revolution; for tariff II, after eight-tenths of one revolution and for tariff III after one complete revolution.

According to whether the apparatus is set 20 for tariff I, II or III, the shaft q is driven by the corresponding worm and drives the sleeve f . As before stated, this sleeve is displaced at the same time so that the finger f' is placed at will in front of one or the 25 other of the steps g^2 , g^3 , g^4 and determines the period at which the registering movement of the shaft is to begin according to the tariff in use. A coil spring r mounted on the shaft tends constantly to press the 30 finger f' axially against the barrel g . A pinion o' which transmits movement to the registering train and is integral with a toothed clutch sleeve l is driven by a ratchet pawl n mounted on the left-hand side of the 35 gland m integral with g . Attached to a pin o on the gland m is one end of a coiled spring m' , the other end of which is attached to the driving shaft q which moves the hub g' forward through a distance corresponding 40 to the amount of lost motion associated with the tariff employed, when the apparatus is set at "free". p is a washer pinned to the shaft q to keep the various parts shown in Fig. 4 in position.

45 The clutch sleeve l may be moved in or out of engagement with the hour pinion H by moving the sleeve l axially against the action of a spring, for instance, by means of a lever actuated by a cam mounted on the 50 flag or setting shaft and engaging a collar k on the sleeve l , for the purpose of freeing the pinion from the registering mechanism when it is desired to record the time wasted in repairs and the like when on hire, which 55 time of course cannot be charged for.

The mechanism is driven in the following manner when actuated by the clock: The usual hour pinion H is arranged on a clutch sleeve j surrounding the barrel g on 60 the shaft q and meshing with the sleeve l . The hour pinion meshes with the clockwork and is provided on one of its faces with a pin h' which engages a finger j' , Fig. 6, fixed on the tooth clutch sleeve j . The time 65 taken by the finger h' to revolve into con-

tact with j' corresponds to the first of the intervals after each of which an increase in the fare is registered. When the apparatus is set at "free", the release of a spiral spring h , of which one end is fixed to the 70 clutch sleeve j and the other extremity to the hour pinion H moves the toothed clutch sleeve to its initial position.

When the flag shaft is rotated to the "free" 75 position, the pinion H is freed from the registering mechanism this permitting the movement of the parts as above described. It is to be noted that the clutch mechanism comprising the pawl n and toothed sleeve l enables the hour pinion to overrun the shaft 80 q while the clutch sleeve j enables the shaft when driven from the road wheel to overrun the hour pinion.

What I claim and desire to secure by Letters Patent is:—

1. The combination with a device for automatically computing and recording the tariff of a hired vehicle, according to the distance traveled, rate charged, time consumed and load carried, of driving means, 90 actuated by the movement of the vehicle, for operating the said device, means for varying the tariff rate by changing the ratio of the speed of the driving means to the driven device, comprising a series of endless screws, driven by said driving means, a series of toothed wheels each of different pitch and each adapted to be driven by one of said endless screws and each of said toothed wheels being adapted to operate said device, and means for controlling said toothed wheels so that any one of the series may be operated whereby the ratio between the driving means and the driven device may be varied according to the rate 95 of tariff to be charged.

2. The combination with a device for automatically computing and recording the tariff of a hired vehicle, according to the distance traveled, rate charged, time consumed and load carried, of driving means, 110 actuated by the movement of the vehicle, for operating the said device, means for varying the tariff rate by changing the ratio of the speed of the driving means to the driven device, comprising a series of endless screws, driven by said driving means, a series of toothed wheels each of different pitch and each adapted to be driven by one of said endless screws, and each of said toothed wheels being adapted to operate 115 said device, and means for controlling said toothed wheels so that any one of the series may be operated whereby the ratio between the driving means and the driven device 120 may be varied according to the rate of tariff to be charged, and automatic means, separate from the driving means, for continuing the operation of the driven device 125 when the said vehicle is at rest.

3. In a taximeter the mechanism for obtaining three different tariffs or rates or registration comprising three endless screws engaging individually with three different
5 worm wheels arranged on a common shaft and adapted to transmit the driving movement of each driving screw to the registering mechanism by a coupling barrel provided with a corresponding number of steps
10 or recesses of varying depth whereby a dif-

ferent delay is obtained in the transmission of the driving movement from each individual driving screw to the registering mechanism.

In testimony whereof I have affixed my 15
signature in presence of two witnesses.

RENÉ PICARD.
